DESIGN FOR SUNGLASSES

George Du Bon, Rosedale, N. Y., assignor to The Glembay Company, Inc., New York, N. Y., a corporation of Delaware

Application November 2, 1937, Serial No. 72,584

Term of patent 14 years

To all whom it may concern:

Be it known that I, George Du Bon, a citizen of the United States, residing in Rosedale, in the county of Queens and State of New York, have invented a new, original, and ornamental Design for Sunglasses, of which the following is a specification, reference being had to the accompanying drawing, forming part thereof.

In the drawing:

Figure 1 is a perspective view of sunglasses showing my new design, and

Figure 2 is a top plan view thereof.

The edges of the eye pieces are curved from the nose-bridge to the portions of greatest height, which are positioned short distances from the nose-bridge. The edges of the eye pieces then extend in substantially straight lines which taper from the portions of greatest height to the curved ear pieces, the temple-bows forming a continuation of the eye pieces.

I claim:

The ornamental design for sunglasses, as shown and described.

GEORGE DU BON.
